SEWING MACHINE

Norman V. Christensen, Chicago, Ill., assignor to
 Union Special Machine Company, Chicago, Ill.,
 a corporation of Illinois

Application September 7, 1946, Serial No. 695,426

7 Claims. (Cl. 112—202)

1

This invention relates to sewing machines and more particularly to machines of the lock stitch and double locked stitch types.

An object of the invention has been to provide for the economical and efficient production on a large scale of sewing machines of the types indicated.

Another object has been to provide a frame structure and suitable mechanisms therefor enabling the employment of many common parts for the production of either a lockstitch or a double locked stitch sewing machine. Toward this end a further object of the invention has been to provide interchangeable saddle units for selective assembly in a frame to provide either a vertical axis rotary hook, lockstitch machine or a vertical axis oscillatory looper, double locked stitch machine.

A still further object of the invention has been to provide for such interchangeable use of rotary hooks and oscillatory loopers in either a needle feed machine or a plain feed machine, i. e., one not provided with needle feed.

In attaining the foregoing objects a number of important, special features have been developed. Of primary importance is the development of a self-contained oscillating looper saddle unit which may be used interchangeably with a vertical hook saddle unit. The arrangement is such that a 1 to 1 driving ratio may be provided between the main rotary shaft in the base of the machine and a shaft within the looper saddle while a 1 to 2 ratio may be provided between said main shaft and the hook carrying shaft of the vertical hook saddle. A sewing machine which is otherwise complete, with or without a needle feed action, may be formed either into a double locked stitch machine by the use of the looper saddle or into a locked stitch machine by the use of the hook saddle. Other minor changes in the machine assembly may be desirable in converting from one type to the other, but these changes are of a character well within the experience of an operator or mill mechanic. They include changes in the type or spacing of the needles, the throat plate, presser foot, thread takeup eyelets, feed dog, and the like.

Another special feature is the provision of an improved vertical rotary hook unit. This is of simple, compact construction and embodies an improved, highly effective lubrication system.

A further feature is the provision of a simple but effective puller mechanism which cooperates with the regular work feeding mechanism to

2

insure the proper and uniform advance of the work. This puller mechanism is of such character that it may readily be applied to or omitted from the machine, depending upon the particular requirements of the machine.

Still another feature of the invention is the provision of either a two-motion or a four-motion looper, as desired, in the vertical axis looper saddle to be embodied in the machine. Both types of loopers are of simple construction and adapted for reliable operation in conjunction with the needle. Moreover, the arrangements are such that a plurality of loopers may readily be incorporated in a single unit for cooperation with a plurality of needles. A single looper may, if desired, cooperate with a plurality of needles. The four-motion loopers are driven by a single driving member which imparts the four motions.

20 The provision of a self-contained lubrication system in each of the looper saddle units is a still further feature of the invention.

Also, the adaptation of the machine for either a rotary takeup, of improved construction, or an oscillatory or reciprocatory takeup, as desired, is still another feature of the invention.

Improved presser means are also provided in conjunction with the work feeding devices. The arrangement is such that separate presser means are provided for the regular, four-motion feed dog and an auxiliary puller roller and means operable at will are provided for disabling both of these presser means simultaneously or for disabling one alone.

30 Other objects, features, and advantages will appear from a detailed description of certain illustrative embodiments of the invention which will now be given in conjunction with the accompanying drawings, in which:

Fig. 1 is a full-sized, top plan view of a part of the work supporting portion of a machine embodying features of the invention, certain cover plates being removed from the work supporting surface to expose the parts beneath;

40 Fig. 2 is a longitudinal vertical section through the major portion of the illustrative machine on a reduced scale, the remainder being shown in front elevation;

Fig. 3 is a view, partly in end elevation and partly in vertical section, taken substantially along the line 3—3 of Fig. 2;

Fig. 4 is a bottom plan view of the machine with a cover plate removed to expose the interior mechanism;

Fig. 5 is a fragmentary view, partly in bottom

plan and partly in horizontal section taken intermediate the top and bottom of the base portion of the machine;

Fig. 6 is a transverse vertical section through the machine taken substantially along the line 6—6 of Fig. 2;

Fig. 7 is a detail view in vertical section through the work supporting portion of the machine, taken substantially along the line 3—3 of Fig. 2, and illustrates a modified form of work feeding mechanism from that shown in Fig. 3;

Fig. 8 is a vertical section through the work supporting portion of the machine taken along the line 8—8 of Fig. 1;

Fig. 9 is a vertical section through a looper saddle unit embodied in the machine and is taken along the line 9—9 of Fig. 1;

Fig. 10 is a schematic view showing in plan a looper carrier provided with a plurality of loopers and operating linkage therefor adapted to impart a four-motion movement thereto;

Fig. 11 is a similar schematic view showing a looper carrier having a single looper mounted thereon, the path of the end of the looper and of other points of the system being indicated;

Fig. 12 is a view in transverse vertical section through the work support, similar to Fig. 8, but showing a modified form of looper which has only a two-motion movement;

Fig. 13 is a vertical sectional view taken along the line 13—13 of Fig. 12;

Fig. 14 is a view similar to Fig. 11 in relation to the two-motion looper of Fig. 12 and shows the path of the two-motion looper;

Fig. 15 is a fragmentary view, in top plan, of the work support of the machine equipped with vertical axis hooks in lieu of the loopers of Fig. 1;

Fig. 16 is a transverse vertical sectional view, similar to Fig. 8, illustrating the vertical axis hook and is taken along the line 16—16 of Fig. 15;

Fig. 17 is a fragmentary detail view, in section along the line 17—17 of Fig. 16, showing a portion of the hook saddle construction;

Fig. 18 is a fragmentary bottom plan view of a portion of the base of the machine embodying the vertical axis hook saddle, a bottom cover plate being removed therefrom;

Fig. 19 is a vertical sectional view through the hook saddle unit, taken along the line 19—19 of Fig. 15;

Fig. 20 is a vertical sectional view through the hook saddle of Fig. 16 and is taken along the line 20—20 of Fig. 16;

Fig. 21 is a fragmentary detail view, in horizontal section, taken along the line 21—21 of Fig. 20; and

Fig. 22 is a fragmentary detail view, in vertical section, taken along the line 22—22 of Fig. 20.

Referring now to the drawings and more particularly to Figs. 1, 2, and 3, the illustrative machine is of the flat bed type embodying a frame having a work supporting portion or base 10, a vertical standard 11 rising from one end of the base, and an overhanging arm 12 extending over the base from the upper end of the vertical standard. Within the overhanging arm there is mounted, in suitable bearings, a main shaft 13 which projects through a wall of the frame and carries at its outer end a combined handwheel and pulley 14. A train of gearing 15 within the vertical standard connects the shaft 13 with a main shaft 16 suitably journalled in the base portion of the frame. Gearing 15 includes a gear secured to each of the shafts 13 and 16 and an

intermediate idler gear mounted for rotation upon a stationary shaft in the standard.

At the free end of the overhanging arm there is carried a needle head 17 in which is mounted for vertical reciprocation a needle bar 18. Suitable bearings 19 and 20 are provided for the needle bar in the needle head. For the purpose of reciprocating the needle bar a crank member 21 is secured to the end of the shaft 13 within the needle head and a crank pin on this member is connected by means of a link or pitman 22 with a collar member 23 secured to the needle bar. At its lower end the needle bar may be provided with a needle carrying frame 24, of any suitable form, serving to support a needle or plurality of needles 25. For the purposes of illustration two needles are shown, these being relatively widely spaced.

Loop-taking mechanism

Referring now more particularly to Figs. 1, 8, and 9, there is provided in one form of the machine, complementary loop-taking means in the form of loopers 26 mounted for oscillation about vertical axes. Each of these loopers is carried by an oscillatable carrier 27 having a relatively large central portion provided with an opening adapted to receive an eccentric portion 28 of a vertically disposed hollow shaft 29. This shaft is mounted for rotation in suitable bearings 30 and 31 carried by an auxiliary frame or bracket or saddle 32 which is adjustably mounted on the base portion of the main frame of the machine. For this purpose the saddle is preferably provided with a forked extension 33 adapted to surround a bearing sleeve 34 (Fig. 4) carried by a fixed lug 35 integral with and extending downwardly from the under surface of the work support. A screw 36 may be provided for drawing the forked ends 33 together to clamp the same in desired position upon the bearing sleeve 34. The opposite end of the saddle is preferably in the form of a lug 37 having an elongated slot 38 extending therethrough and adapted to receive a screw 39 which has threaded engagement with a lug 40 on the base portion of the main frame. When the screws 36 and 39 are loosened the saddle may be shifted axially along the shaft 16 to any desired position and it may then be clamped in set position by tightening the screws 36 and 39. Adjustment may thus be made for any desired needle spacing and positioning.

For the purpose of driving the shaft 29 there is mounted on the shaft 16 a spiral gear 41 arranged to mesh with a companion spiral gear 42 which is secured to the shaft 29 by means of a set-screw 43. Gear 41 is adjustable axially along the shaft 16, to conform with the adjustment of the saddle unit as explained above, and is secured to the shaft for rotation by means of a set screw, as shown in Fig. 3. At its upper end the shaft 29 has a crank pin extension or second eccentric 44, above the eccentric 28, which is adapted to receive one end of a link or connecting rod 45. The opposite end of said link is secured by a screw 46 to a lever 47 pivotally supported on the saddle unit by means of a pin 48 held in place by a set screw 49. The outer free end of the lever 47 is secured by means of a screw 50 to one end of a link 51, the opposite end of which is secured by a screw 52 to the looper carrier 27.

It will be apparent that due to the mounting and operating linkage described with respect to the carrier 27, the latter will be rocked about the eccentric portion 28 of the shaft through the

action of the crank pin 44, while, at the same time, carrier will be shifted bodily due to the rotation of the eccentric 28 within the cooperating circular portion of the carrier. Referring to Fig. 11, there is indicated diagrammatically the paths of movement of various elements of the looper structure. Thus the axis of the eccentric 28 will be carried through the circular orbit designated 53, whereas the axis of the crank pin 44 will be carried through the larger circular orbit 54. These combined movements will impart to the free end of the looper 26 the path indicated by the arrows and the crescent 55, by virtue of the bodily movement imparted to the carrier 27 by the eccentric 28 and the rocking movement imparted to this carrier by the crank pin 44 through the link 45, lever 47 and link 51. The corresponding relative positions of the parts for each 30° of rotation of the shaft 29 are indicated by the numerals 0 to 11 inclusive around the several orbital paths described above. In Fig. 11 the parts are shown in the positions they assume at point 7 in the cycle of rotation of shaft 29. From the path designated 55 it will be seen that the looper is not only oscillated to pick up and shed one or more needle loops, but it is also given a needle avoid movement.

In Fig. 10 there is shown the possibility of mounting a plurality of loopers 26a and 26b upon the same looper carrier 27a. This carrier may be so mounted as to receive the same four-motion movement as described in connection with Fig. 11. The arrangement may be such that each looper cooperates with a needle, 25a or 25b, the foremost and rearmost positions of which are indicated in Fig. 10 for a needle feed machine. Thus a single looper carrier may bring about the production of two lines of stitching, each involving three threads, i. e., a looper thread and two needle threads. It will be understood that each looper may cooperate with but a single needle, if desired.

Means are preferably provided for automatic lubrication of the principal wear surfaces in the looper unit. For this purpose, a lubricant reservoir 56 is provided directly in the bracket or saddle, the lubricant being introduced into this reservoir through an inlet opening at the top which is accessible through the work supporting surface upon the removal of a small plate 10a (Fig. 8). This inlet opening is then preferably closed by a Gits cup cap 57. A lucite gauge 58 is also preferably provided to indicate at all times the quantity of lubricant in the reservoir. The lubricant is delivered from a point adjacent the bottom of the reservoir through a small sleeve 59 into the interior of which the oil passes through small openings 60 in the wall of the sleeve. At the inner end of the sleeve a restricted passage 61 is provided for conducting the oil into a small pocket 62 formed at the base of the shaft 29. Since it is important to limit the quantity of lubricant supplied to the various bearing surfaces, particularly those which are exposed and likely to sling any excess oil in such directions as to soil the work or the stitching thread, a needle valve 63 is provided in cooperation with the passage 61 to accurately regulate the flow of oil from the interior of the sleeve 59 through the passage 61 to any extent desired. The outer end of the stem of the needle valve is enlarged and screw-threaded, as indicated at 64, to cooperate with threads on the interior of the sleeve 59. The end of the stem may be provided with a slot to receive a screw-driver for appropriate adjustment. A

lock nut 65 serves to hold the stem in any position to which it may be adjusted.

To elevate the oil from the pocket 62 to the various surfaces to be lubricated, a spirally grooved core pin 66 is provided within a bore extending axially of the shaft 29. A relatively loose fit exists between the pin and the bore of the shaft. At its lower end the core pin has a flattened extension 67 cooperating with a slot or groove 68 formed in the upper surface of a bottom closure plate 69 for the reservoir 56 and pocket 62. This bottom closure plate may be secured to the hook saddle in any suitable way, as by means of screws and it should be appropriately gasketed. It will be apparent that due to the construction described, the core pin will remain stationary while the shaft is rotated and, as a result, the oil will be drawn upwardly from the pocket 62 along the inclined or spiral groove in the core pin by a viscous pump action. At the upper end of the core pin a part of the lubricant will be discharged through a small passage 70 to the cooperating surfaces between the eccentric 28 and the cylindrical portion of the looper carrier 27. Another part of the oil will be directed upwardly through the passage 71 extending axially of the crank pin 44. A laterally extending passage 72 then serves to direct this lubricant to the cooperating surfaces between the crank pin and the pitman 45. If desired, a portion of the lubricant pumped by the action of the core pin may be discharged laterally through small passages, not shown, to the cooperating surfaces between the shaft 29 and the bearing members 30 and 31. However, other means of lubrication of these bearings may be, and preferably are, provided.

In Figs. 12, 13, and 14, a slightly modified form of looper unit is illustrated. In this modified construction the shaft 29 is provided with an enlarged concentric portion 73, in lieu of the eccentric 28, about which a looper carrier 74 may be oscillated. This looper carrier may be provided with one or more loopers 75 attached by means of a screw 76 or the like. In other respects the construction of the modified unit may be identical with that previously described. By elimination of the eccentricity of the portion 28 of the looper operating shaft, the looper will be given a simple oscillatory movement along the path 77 of Fig. 14. Because of the arcuate form of the looper 75, it has been found that proper stitch formation may readily be achieved without the necessity of a four-motion movement of the looper.

Vertical hook units

The machine, as hereinabove described, is capable of being readily converted from a double locked stitch machine to a regular or single lock stitch machine by the simple substitution of a different type of saddle for the looper saddle described above. Thus, referring to Figs. 15 to 22 inclusive, there may be substituted for the looper saddle a vertical axis hook unit comprising a bracket or saddle 78 having a forked extension 79 adapted to be adjustably mounted upon the bearing sleeve 34 and locked in adjusted position thereon by a screw 80. At its opposite end the saddle may be provided with a lug 81 having an elongated slot 82 adapted to receive a screw 83 for adjustable attachment of this end of the saddle to the lug 40 of the main frame of the machine. It will be seen, in general, that the vertical hook unit may be employed interchange-

ably with one or another of the looper units above described to provide a lockstitch machine or a double lockstitch machine, as desired.

A vertically disposed hook carrying shaft 84 is journalled in suitable bearings 85 and 86 carried by spaced projecting portions of the hook saddle. A spiral gear 87 secured to the shaft in any suitable way intermediate the bearings 85 and 86 is arranged to be driven by a spiral gear 88 secured to the shaft 16. Gear 88 is shiftable axially along the shaft 16 to correspond with the adjustment of the hook saddle and is secured in any desired position by a set-screw. The relationship between the gears 87 and 88 is such that the hook shaft 84 will be given two revolutions for each revolution of the shaft 16. Between the upper surface of the gear 87 and the under surface of the bearing 85, a spacing and thrust bearing plate 89 is provided. Extending upwardly from the lower arm of the hook saddle adjacent the bearing 86 is a small ledge 90, as best shown in Figs. 16 and 17, which serves to prevent the gear 87 from falling out when the hook shaft 84 is removed for purposes of inspection or repair and when the machine is then tilted back on its supporting table. The rotary hook comprises a rotating component 91, secured to the upper end of the shaft 84 by means of a set-screw 92, and a stationary component 93 forming a bobbin case holder. This stationary component is provided with laterally projecting ribs 94 arranged to cooperate with a raceway 95 in the rotating component, in a manner well known in the art.

A finger 96 is provided for engagement with a projection 97 on the bobbin case holder for the purpose of shifting this holder slightly in a counterclockwise direction (Fig. 15) at a point in the stitch forming cycle at which the needle thread loop is to be pulled away from a retainer (not shown) that normally engages the bobbin case holder to restrain it against rotation with the rotary component of the hook. The loop releasing finger 96 is adjustably carried by an arm 98 which is forked to receive the upper end of a shaft 100 to which it is clamped by means of a screw 99. The shaft 100 is journalled in bearings 101 and 102 carried by the hook saddle. A screw 103 may be provided at the top of the shaft 100 to assist in locking the arm 98 in the desired position on the shaft. At its lower end the shaft 100 has secured thereto, in any suitable way, an arm 104 to which is pivotally connected, by means of a bolt 105, the outer end of a pitman 106 having a strap portion surrounding an eccentric 107 carried by the shaft 84 adjacent its lower end. The connections described are such that upon rotation of the shaft 84, the arm 104 and shaft 100 will be rocked at an appropriate point in the cycle to carry the finger 96 against the projection 97 for the purpose hereinabove mentioned.

Provision is made for automatic lubrication of the major wear receiving surfaces of the hook unit. For this purpose the saddle is provided with a relatively large oil reservoir 108, at one side of the shaft 84, and a smaller reservoir 109, extending around the lower end of the shaft 84 and housing the eccentric 107, pitman 106, arm 104, and the lower end of the shaft 100. A removable closure plate 110 is provided for closing the bottoms of the two reservoirs 108 and 109. This closure plate may be secured to the hook saddle in any suitable way, as by means of screws, and

an oil tight connection may be insured by the provision of a gasket.

Lubricant may be supplied to the reservoir 108 through an opening in the top which is accessible through the work supporting surface of the machine upon the removal of a small plate 10b (Fig. 16), the inlet for this purpose being preferably closed by a spring urged cap 111. The quantity of oil present in the reservoir may be indicated at all times by means of a lucite oil gauge 112 visible upon the removal of plate 10b. The lubricant is delivered from the reservoir 108 through a filter screen 113 secured to the bottom closure 110 by means of a screw 114. After passing through the filter the lubricant enters a small pocket 115 in the closure plate and is then delivered laterally through a small bore 116 in this plate to and through a small aperture 117 in a hollow stud 118 which extends through the bottom closure plate. Stud 118 preferably has a head or radially extending flange at its lower end which engages the underside of the closure plate and may be secured thereto by solder or the like. A sufficiently tight fit is provided between the stud and the closure plate to prevent leakage of oil. Oil which passes through the aperture 117 into the interior of the stud rises through the latter and through a small aperture 119 adjacent the upper end of the stud into the bore of the shaft 84. This is due to the head of the oil in the reservoir 108. Stud 118 remains stationary and is provided with a bearing fit in relation to the inner surface of the bore of the shaft 84. This fit is sufficiently close to prevent the passage of any substantial amount of oil from the top of the stud downwardly along its outer surface into the reservoir 108. Should any small quantity of oil follow this path, there is no serious objection, although preferably the lubricant retained within the reservoir 109 is of a different character from that within the reservoir 108.

A needle valve 120 having an enlarged screw threaded head 121 cooperating with threads at the lower end of the stud 118 may be adjusted to regulate accurately the amount of lubricant delivered through the aperture 119 into the bore of the shaft 84 during the operation of the machine. A lock nut 121a may be provided to lock the needle valve in adjusted position. Within the bore of the shaft 84 there is carried, with a relatively loose fit, a spirally grooved core pin 122 having at its lower end a downwardly projecting tongue 123 which is slotted in line with the aperture 119, as best shown in Fig. 22. The tongue 123 is arranged to fit between two upwardly extending segments 124 at the upper end of the stud 118. The arrangement is such that the pin 122 is supported by the upper end of the stud 118 and is prevented from rotation with the shaft 84 by the cooperation of the elements 123 and 124. At the same time a passage is provided around these coacting parts so that the lubricant may rise in the bore of the shaft 84 and along the spiral groove of the core pin. Upon rotation of the shaft 84 a viscous pump action is established by which the oil is lifted along the spiral groove to the top of the shaft 84 and is discharged into a small pocket 125 within the rotary component of the hook. From this pocket the oil is discharged by centrifugal force through a small tube 126 which conducts the oil to the raceway 95. It will be understood that by proper adjustment of the needle valve 120 just the right amount of lubricant may be supplied to the raceway, so that the

hook will not overheat and yet no oil will be thrown during its rapid rotation.

Work feeding devices

Feeding of the work across the work supporting surfaces in the formation of seams may be accomplished in a number of different ways. In the principal illustrative embodiment of the invention the means for this purpose includes a four-motion feed dog and an auxiliary roller feed or puller mechanism. The latter may, if desired, be omitted. Moreover, the action of the feed dog may be supplemented by a needle feed movement of the needle bar, whenever desired.

Referring now particularly to Figs. 1 to 6 inclusive, a feed dog 127 of appropriate form may be provided, the serrated or toothed portion of the feed dog being arranged to extend upwardly through slots in the usual throat plate provided in the work supporting surface. The feed dog is carried by a feed bar 128 to which it is adjustably secured by screws 129 and 130. Feed bar 128 is pivotally connected at 131 with a feed rocker 132 secured to a shaft 133 suitably journaled in bearings provided in the base of the machine. In the portion of the base directly below the vertical standard 11 there is secured to the shaft 133 a yoke 134 of generally U-shaped configuration. This yoke is clamped to the shaft by means of a screw 135. One of the arms of the yoke carries at its outer end a laterally extending pin 136 cooperating with a strap at the lower end of a connecting rod 137 whose upper end is similarly connected with a pin 138 carried by an arm 139 secured to a rock member 140. The pins 136 and 138 and the strap portions of the rod 137 are preferably provided with spherical cooperating surfaces. Member 140 in the construction illustrated is adapted to rock about the axis of shaft 13. It may, for this purpose, be freely mounted upon an extension of the adjacent bearing for this shaft. If it is desired to provide the machine with a needle feed action, on the other hand, the member 140 will be secured to a sleeve capable of transmitting the motion of the member to a frame in the needle head in which the needle bar is slidably mounted. A suitable arrangement of this character is disclosed in the Christensen application, Serial No. 582,876, filed March 15, 1945.

A sleeve-like member 141 (Fig. 6) is provided with a lateral extension having a strap arranged to cooperate with an eccentric 142 secured to shaft 13. Slidably within the sleeve 141 is a rod 143 to which is secured a yoke or collar 144 carrying a pin 145 providing a pivotal connection with a member 146 secured to a rod 147. The latter is adjustably mounted for axial sliding movement in suitable bearings in the frame of the machine. Vertical adjustment of the rod 147 may be effected by turning the knurled head 148 of a member which has a screw-threaded stem that engages threads in and supports the rod 147. A lock nut 149 cooperating with threads on the member 148 serves to lock the parts in adjusted position. Below the collar 144 there is slidably mounted on the rod 143 a collar 150 which is pivotally connected at 151 with the lower end of the rock member 140. The foregoing arrangement is such that as the shaft 13 is rotated the sleeve 141 will be shifted bodily in a circular path due to the action of the eccentric 142. The up and down movements of the sleeve will cause it to rock the rod 143 about the pivot 145. Such rocking movements of the rod

will, in turn, be imparted through the collar 150 to the lower arm of the member 140. The extent of rocking of the member 140 may be varied by varying the position of the pivot 145 through adjustment of the knurled member 148. For further details as to the construction and operation of this mechanism reference may be had to said Christensen application, Serial No. 582,876.

Rocking of the member 140 in the manner explained will impart corresponding rocking movements to the yoke 134 and to the shaft 133 so that the feed rocker 132 will impart the feed and return movements to the feed dog 127. In synchronism therewith the feed dog will be lifted and lowered by means of an arm 152 connected at one end with the feed bar and at its opposite end pivotally connected with a strap member 154 cooperating with an eccentric 155 carried by the shaft 16.

The other arm of the yoke 134 is provided with an elongated slot 156 along which a bolt 157 may be adjusted and then secured in any desired position. This bolt provides a pivotal connection with a link 158 attached at its upper end by a screw 159 to an arm 160 integral with a driving plate 161 of a one-way roller clutch of the type disclosed in the Long, et al. Patent No. 1,692,130, granted November 20, 1928. A spool-like member 162 which encloses the rollers and other internal mechanism of the clutch is secured to a shaft 163 which is mounted in suitable bearings in the base of the frame and which extends into the region of the line of feed of the work. A plate 164 at the opposite end of the spool from the plate 161 has a bent-over extension 165 which is secured by screws 166 to a part of the frame. This plate 164 carries the part of the clutch structure which prevents retrograde movement of the spool during the reverse or idle movements of the driving plate 161. For further details as to the construction and operation of the clutch, reference may be had to said Long, et al. patent. To the forward end of the shaft 163 there is secured a feed roller 167 which may be suitably grooved, serrated, or knurled, if desired, to assist in feeding the work.

Suitable presser members are provided to cooperate with the feed dog 127 and the feed roller 167 in advancing the work. Referring to Fig. 3, a presser foot 168 carried by a presser bar 169 cooperates with the feed dog 127. The presser bar is mounted for vertical movement in suitable bearing sleeves in the needle head and is normally urged downwardly by a spring 170 cooperating at its upper end with the bottom of a screw threaded sleeve 171 which may be adjusted to vary the tension of the spring. At its lower end the spring engages a block 172 secured to the presser bar. Lifting of the presser bar to permit insertion and removal of the work is accomplished by a sleeve 173 slidably mounted on the presser bar and connected by a link 174 with an arm 175 carried by a rock shaft 176. The latter is suitably journaled in the overhanging arm of the frame and at a point adjacent the vertical standard is provided with a rearwardly extending arm 177 (Fig. 6) which is connected by a rod 178 with a suitable foot treadle for controlling the lifting of the bar. The linkage for this purpose may include a rocker member 178a rockably mounted on the rear side of the base of the machine beneath the work supporting surface.

For cooperation with the auxiliary feed or puller roller 167 there is provided a separate 75 tachable frame member 179 adapted to be se-

cured by screws or the like (not shown) to the needle head of the main frame. Suitably mounted in the auxiliary frame for vertical reciprocation is a bar 180. A yoke 181 is secured to the lower end of this bar and supports a horizontally disposed shaft 182 which carries a presser roller 183 arranged to cooperate with the feed roller 167. For the purpose of yieldingly urging the presser roller 183 against the feed roller a spring 184 is provided around the bar 180 and is arranged to cooperate with the lower end of a threaded sleeve 185 which may be turned to adjust the tension of the spring. The lower end of the spring acts against a lug 186 secured to the bar 180. For the purpose of lifting the presser roller 183 against the action of the spring, a lever 187 is provided, this having a camming portion adapted to engage an extension of the lug 186. A downwardly and forwardly extending hooked portion 187 of the lug 186 is arranged to engage beneath a projection 188 integral with the sleeve 173. This arrangement is such that upon the lifting of the bar 180 by operation of the lever 187 the presser bar 169 will also be lifted.

In machines in which the auxiliary roller feed or puller mechanism is not desired, a somewhat different construction of the feed dog operating mechanism may be employed. Referring to Fig. 7, a shaft 189 corresponding with the shaft 133 of Figs. 3, 4, and 6, may be provided, this being at a somewhat higher point in the base of the machine than the shaft 133. It may be operated in substantially the same manner as the shaft 133 through the use of a somewhat shorter connecting rod than rod 137 but similar to the latter. In the region of the feed dog the shaft 189 has secured thereto a feed rocker 190 to which is pivotally connected, adjacent its upper end, a feed bar 191 which carries a feed dog 192. The latter is secured thereto and adjusted by means of screws 193 and 194. A forwardly and downwardly extending arm 195 rigidly secured to the feed bar and pivotally connected at its free end to a strap 196 cooperating with an eccentric 197 carried by the shaft 16, serves to impart the lifting and lowering movements to the feed dog. Means are thus provided for imparting a four-motion movement to the feed dog.

As previously indicated, the machine provided with either of the feed mechanisms above described may also have a needle feed action of the type disclosed in said prior Christensen application.

The machine may be equipped with any of the usual accessory devices provided in machines of the general character to which the invention relates. For example, rotary thread take-up mechanism indicated generally at 198 in Fig. 2 may be provided. This may be driven by a shaft 199 which extends throughout the length of the overhanging arm and which is connected by gearing 200 with the main drive shaft 13. For further details as to a suitable form of construction of such a rotary takeup, reference may be had to the above mentioned Christensen application, Serial No. 582,876. Such a rotary take-up will ordinarily be provided only when vertical hook units are employed to produce a lockstitch machine. A simple reciprocatory or oscillatory take-up of known construction, such as that shown in the application of Norman V. Christensen, Serial No. 513,336, filed December 8, 1943, may be advantageously employed in the double lockstitch machine.

Reference may be had to said prior Christen-

sen application for other details of the machine, such as the thread tensioning devices shown generally at 201 in Fig. 2.

While a primary embodiment of the invention, 5 and various modifications, have been illustrated and described in considerable detail, it will be understood that various changes may be made in the construction and operation of the various parts of the machine without departing from the general principles and scope of the invention.

What I claim is:

1. In a sewing machine having a frame with a work support provided with a drive shaft, a self-contained loop-taking unit comprising a saddle detachable from said frame, a rotary shaft in said saddle, gearing interconnecting said shafts, a loop-taker mounted on said saddle for oscillation substantially about the axis of said shaft in said saddle, and connections from said rotary shaft to said loop-taker for oscillating the

15 2. In a sewing machine having a frame with a work support provided with a drive shaft, a self-contained loop-taking unit comprising a saddle detachable from said frame, a rotary shaft in said saddle, means interconnecting said drive shaft with said rotary shaft for driving the latter, a loop-taker mounted for oscillation substantially about the axis of said rotary shaft, and connections from said rotary shaft to said loop-taker for oscillating the same, said connections comprising a lever pivotally mounted on said saddle, a link connecting said lever with said loop-taker, eccentric means on said rotary shaft, and a pitman connecting said eccentric means with said lever.

25 3. In a sewing machine having a frame, a loop-taking unit comprising a saddle detachable from said frame, a rotary shaft in said saddle, a loop-taker mounted for oscillation substantially about the axis of said shaft, connections from said shaft to said loop-taker for oscillating the same, and connections between said shaft and said loop-taker for imparting bodily movements thereto.

30 4. In a sewing machine having a frame, a loop-taking unit comprising a saddle detachable from said frame, a rotary shaft in said saddle, a loop-taker mounted upon an eccentric portion of said shaft for oscillation substantially about the axis of said shaft, and connections from said shaft to said loop-taker for oscillating the same.

35 5. In a sewing machine having a frame, a self-contained loop-taking unit comprising a saddle detachable from said frame, a rotary shaft in said saddle, a loop-taker mounted for oscillation substantially about the axis of said shaft, connections from said shaft to said loop-taker for oscillating the same, said connections including eccentric means carried by and rotatable with said shaft, a lubricant reservoir in said saddle, and means operable upon rotation of said shaft for distributing lubricant from said reservoir to bearing surfaces of said eccentric means, said lubricant distributing means including a passage formed in said eccentric means and means within said shaft and operable to transmit lubricant from said reservoir to said passage.

40 6. In a sewing machine having a frame with a work support provided with a drive shaft, a self-contained loop-taking unit comprising a saddle detachably connected with said frame, a rotary shaft in said saddle, means interconnecting said drive shaft with said rotary shaft for driving the latter, a looper carrier mounted on

said rotary shaft for oscillation thereon, a plurality of loopers carried by said carrier, and connections from said rotary shaft to said carrier for oscillating the same and said loopers.

7. In a sewing machine having a frame, a self-contained loop-taking unit comprising a saddle detachable from said frame, a rotary shaft in said saddle, a loop-taker mounted for oscillation substantially about the axis of said shaft, connections from said shaft to said loop-taker for 10 oscillating the same, said connections including eccentric means carried by and rotatable with said shaft, a lubricant reservoir in said saddle, and means for distributing lubricant from said reservoir to bearing surfaces of said eccentric 15 means, said lubricant distributing means comprising pump means associated with said shaft and rendered effective upon rotation of said shaft and a passage formed in said eccentric means and communicating with said pump means. 20

NORMAN V. CHRISTENSEN.
